STORAGE BAG FOR FOOD OR SIMILAR ARTICLE

Richard H. Camp, P.O. Box 62, Haines, Oreg. 97833

Filed Apr. 28, 1971, Ser. No. 138,401

Term of patent 14 years

Int. Cl. D3—99

U.S. Cl. D87—1

FIG. 1

FIG. 2

FIG. 3

FIG. 4.

FIG. 1 is a front perspective view of a storage bag for food or similar article embodying my new design:

FIG. 2 is a rear perspective view;

FIG. 3 is a view similar to FIG. 1 but with the top cover in an open position; and

FIG. 4 is an another front perspective view but with the top cover in an open position and the integral inner liner exposed.

I claim:

The ornamental design for a storage bag for food or similar article, substantially as shown and described.
